(57) **CLAIM**

The ornamental design for a vape pen cartridge protection sleeve as shown and described.

DESCRIPTION

FIG. 1 is an isometric operational view of a vape pen cartridge protection sleeve showing my new design protecting an e-liquid tank/cartridge of a vape pen; FIG. 2 is an isometric view thereof; FIG. 3 is a front elevational view thereof protecting the e-liquid tank/cartridge of the E-cigarette; FIG. 4 is a top plan view thereof; FIG. 5 is a bottom plan view thereof; FIG. 6 is a right side elevational view thereof; FIG. 7 is a left side elevational view thereof; FIG. 8 is a rear elevational view thereof protecting the e-liquid tank/cartridge of a vape pen; and FIG. 9 is a bottom perspective view showing my design. The broken lines shown in the drawings depict environment structure and portions of the vape pen cartridge protection sleeve that form no part of the claimed design.
